UNITED STATES PATENT OFFICE.

JOHN R. KELLER, OF CRAFTON, PENNSYLVANIA, ASSIGNOR TO THE RAIL JOINT COMPANY, OF NEW YORK, N. Y., A CORPORATION OF NEW YORK.

INSULATED RAIL-JOINT.

1,110,291.

Specification of Letters Patent.

Patented Sept. 8, 1914.

Application filed June 4, 1914. Serial No. 843,044.

To all whom it may concern:

Be it known that I, JOHN R. KELLER, a citizen of the United States of America, residing at Crafton, in the county of Allegheny and State of Pennsylvania, have invented new and useful Improvements in Insulated Rail-Joints, of which the following is a full, clear, and exact description, reference being had to the accompanying drawings, which form part of this specification.

This invention relates to devices for joining the meeting ends of rail sections and has particular reference to joint structures of the insulated type.

As such a device I aim to provide a construction which affords direct metallic contact of splice bars with rails, with resultant increased strength of joint; in which the insulating element or elements are preserved or protected from wear or destruction; and in which the splice bars may be formed by rolling and are interchangeable or reversible.

I also aim to provide new and improved details of construction, as will be herein-after more fully described.

I will now describe my invention, referring to the accompanying drawings, so that others skilled in the art to which it appertains may understand and construct the same, it being premised, however, that changes may be made in the structure shown which would not depart from the broad principle of my invention.

Figure 1 is a longitudinal elevational view of an insulated rail joint embodying my invention; Fig. 2 is a transverse vertical sectional view on the line 2—2 of Fig. 1; Fig. 3 is a similar view on the line 3—3 of Fig. 1; Fig. 4 is a longitudinal elevational view of a rail joint showing my invention as embodied in a structure employing straight splices or splice bars without extending base flanges; Fig. 5 is a fragmentary vertical sectional view on the line 5—5 of Fig. 4; Fig. 6 is a similar view on the line 6—6 of Fig. 4; Fig. 7 is a perspective view showing a splice bar which may be used in building a joint embodying my invention, and showing more particularly an inner section of splice of the joint shown in Figs. 4, 5 and 6; and Fig. 8 is a similar view showing an outer section of said splice.

Referring to Figs. 1, 2 and 3, the numerals 2 and 3 indicate the abutting ends of rail sections to be joined by means of splice bars 4 which in this particular case are shown as angle splice bars. Each bar is made up of a plurality of sections one or more of which is provided with rail engaging upper and lower surfaces. As shown, each splice bar 4 is composed of sections 5 and 6 the former of which has a foot or angle flange extending the whole length, or substantially the whole length of the joint, while the section 6 also contacts with the base flange of the rail and has an upper portion or head 6^a which engages the underside of the rail head. Both splice sections 5 and 6 are formed to interlock in such manner that there is afforded a mutual support of great strength. Thus the section 5 has an inner longitudinal recess or channel 7 into which extends a relatively narrower portion 8 of the section 6; the parts being formed to present proper and desirable coacting bearing surfaces 5^b, 8^a and 5^c, 8^e. Furthermore the head portion 6^a of the section 6 overhangs the body of the section 5, being provided with a bearing or thrust face 6^b. Disposed between the splice sections 5 and 6 is an insulating element 9 that so extends as to insulate the portion 8 of the section 6 from the section 5 and to also insulate the larger body portion of the section 6 from the section 5 and the base of the rail section 3; the insulating strips having a foot extension 10 lying between the foot flange of the splice section and the base of the rail. To permit of the insulator 10 being interposed between the foot flange and the base, the former is offset, as at 4^a. This enables the employment of a full extension foot flange and insures proper insulation and full bearing value. It also enables the employment of a splice having a suspending or depending truss or flange, as indicated in Fig. 1 by the letter *a*. This depending flange or truss may be of the usual or any desired cross-sectional shape, as will be apparent without necessity of specific illustration. Tightening bolts 11 secure the splice bars to the rail, in the usual manner. By them not only is the bar section 5 drawn home so that the bearing faces 12 and 13 of the head and

foot respectively are clamped to position, but they also tie the sections together and clamp the section 6 to its rail section 3. Anti-spreading washers or pieces 14 may be interposed between the portion 8 of the splice bar 6 and the web of the rail, where there would be any tendency to spreading, so that with tightening of the bolts 11 the interlocking portions of the bar will be drawn together. Interposed between the rail ends is an insulating strip 9^a, and bolts of one-half of the joint may be provided with suitable insulating sleeves and washers. Thus the bolts that pass through the rail section 3 may be provided with insulating sleeves 15 and 16 to insulate the bolts from the splice bars and rail respectively.

In Fig. 4 I show my joint as embodied in the "straight" type, *i. e.*, one not employing a splice bar of the general "angle" outline. In this view the splice bars 4' are formed of sections 5' and 6' both of which contact with the rail in a manner similar to that of the construction of Figs. 1, 2 and 3. These sections 5' and 6' interlock, by means of the recesses 7' and extending portions 8', as in the case of the splice sections 5 and 6. In the absence of a foot flange, the section 5' has an extending portion 4^b which is bolted to the section 6' by the bolts 11; the section 6' having an overhanging head portion 6'' and a lower head or base or foot member 6^b between which the extension 4^b is disposed. Insulation strip 9' is disposed between the interlocking splice bar section in a manner similar to that of positioning the insulation 9 between sections 5 and 6 of the angle splice bar arrangement. However, in the present form of joint, the insulating element 9' is not provided with an extended foot portion 10, as said portion is not necessary in view of the absence of a foot flange on the splice bar.

I do not desire to limit myself to any particular form of bar or type of joint. As shown in Fig. 6, the splice section 6' may be shaped so as to project at the head in the manner indicated at 6^a. As shown in Fig. 4, the joint may be provided with a base support or plate *b* between which and the rails or splice bars may be interposed insulation 9^b.

Having thus described my invention, what I claim and desire to secure by Letters Patent is:

1. In a rail joint, the combination with the meeting ends of rail sections, of a splice bar formed of a plurality of interlocking members each extending along both rail ends and having upper and lower rail engaging faces, and insulation disposed between said interlocking members.

2. In a rail joint, the combination with the meeting ends of rail sections, of a splice bar formed of a plurality of interlocking

members having upper and lower faces directly engaging the rails, and insulation disposed between said interlocking members and between one of said members and a rail.

3. In a rail joint, the combination with the meeting ends of rail sections, of a splice bar formed of a plurality of interlocking members having upper and lower faces directly engaging the rails, and insulation disposed between said interlocking members and between one of said members and a base flange of a rail.

4. In a rail joint, the combination with the meeting ends of rail sections, of a splice bar formed of a plurality of interlocking members having alining upper rail engaging faces and one of which has a lower rail engaging face, and insulation disposed between said members and between one of said members and a rail face.

5. In a rail joint, the combination with the meeting ends of rail sections, of a splice bar formed of a plurality of interlocking members each extending along both rail ends and each of which is provided with upper and lower rail engaging faces, and insulation disposed between said interlocking members.

6. In a rail joint, the combination with the meeting ends of rail sections, of a splice bar formed of a plurality of interlocking members each extending along both rail ends and each of which is provided with a face engaging the under side of the rail head and with a face engaging a base flange of a rail section, and insulation disposed between said interlocking members.

7. In a rail joint, the combination with the meeting ends of rail sections, of a splice bar formed of a plurality of interlocking members having alining upper and lower rail engaging faces, and insulation disposed between said members and between one of said faces and a rail face.

8. In a rail joint, the combination with the meeting ends of rail sections, of a splice bar formed of a plurality of interlocking members each extending along both rail ends and each of which is provided with upper and lower rail engaging faces, and a strip of insulation extending longitudinally between said members.

9. In a rail joint, the combination with the meeting ends of rail sections, of a splice bar formed of a plurality of interlocking members each extending along both rail ends and having alining upper and lower rail engaging faces, and a strip of insulation longitudinally interposed between said members.

10. In a rail joint, the combination with the meeting ends of rail sections, of a splice bar member having upper and lower rail engaging faces, a complementary splice bar member extending along both rail ends and

bolted to the first member and having an upper rail engaging face, and insulation extending between the bar members.

11. In a rail joint, the combination with the meeting ends of rail sections, of a splice bar member having upper and lower rail engaging faces, a complementary splice bar member bolted to the first member and having an upper rail engaging face, and insulation extending between the bar members and between the complementary bar member and a rail face.

12. In a rail joint, the combination with the meeting ends of rail sections, of a splice bar member having upper and lower rail engaging faces and a head portion, a complementary bar member having a rail engaging face and secured to said first member and having a portion underlying the said head portion, and insulation extending between said bar members.

13. In a rail joint, the combination with the meeting ends of rail sections, of a splice bar member having upper and lower rail engaging faces and a head portion, a complementary bar member having a rail engaging face and secured to said first member and having an extending body portion underlying the said head portion, and insulation extending between the bar members and between the complementary bar member and a rail face.

14. In a rail joint, the combination with the meeting ends of rail sections, of splice bars arranged at each side of the rails and comprising a plurality of members each having upper and lower rail engaging faces engaging one rail section, and a plurality of complementary bar members engaging the other rail section, and insulation extending between said bar members.

15. In a rail joint, the combination with the meeting ends of rail sections, of splice bars arranged at each side of the rails and comprising a plurality of coöperative bar members one set of which engages one rail at each side thereof and extending along the

other rail and another set of which engages the other rail at each side thereof and extending along the first rail, and insulation 50 extending between said bar members.

16. In a rail joint, the combination with the meeting ends of rail sections, of splice bars arranged at each side of the rails and comprising a plurality of interlocking bar 55 members one set of which engages one rail at each side thereof and extending along the other rail and another set of which engages the other rail at each side thereof and extending along the first rail, and a strip of 60 insulating material extending between said interlocking bar members.

17. In a rail joint, the combination with the meeting ends of rail sections, of splice bars arranged at each side of the rails and 65 comprising a plurality of coöperative bar members one set of which engages one rail at each side thereof and another set of which engages the other rail at each side thereof, and a strip of insulating material extending 70 between said coöperating bar members and between one set of said members and a rail section.

18. In a rail joint, the combination with the meeting ends of rail sections, of a splice 75 bar formed of a plurality of coextensive interlocking members each member having upper and lower rail engaging faces, and insulation disposed between said interlocking members.

19. In a rail joint, the combination with the meeting ends of rail sections, of a splice bar formed of a plurality of coextensive interlocking members having alining upper rail engaging faces and one of which has a 85 lower rail engaging face, and insulation disposed between said members and between one of said members and a rail face.

In testimony whereof I have hereunto set my hand.

JOHN R. KELLER.
